(57) **CLAIM**

The ornamental design for a smokeless fire pit, as shown and described.

DESCRIPTION

FIG. 1 is a front, left, top perspective view of a smokeless fire pit, showing my new design;

FIG. 2 is a rear, right, bottom perspective view thereof;

FIG. 3 is a top perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is a front, bottom perspective view of the smokeless fire pit in the second state; and,

FIG. 11 is a front, bottom perspective view of the smokeless fire pit in the third state.

The dashed broken lines in the figures are for the purposes of illustrating portions of the smokeless fire pit and form no part of the claimed design.

1 Claim, 11 Drawing Sheets
